UNITED STATES PATENT OFFICE.

JOHNATHAN L. WELDON, OF KOPPERL, TEXAS.

PLOW.

SPECIFICATION forming part of Letters Patent No. 760,767, dated May 24, 1904.

Application filed September 23, 1903. Serial No. 174,355. (No model.)

To all whom it may concern:

Be it known that I, JOHNATHAN L. WELDON, a citizen of the United States, residing at Kopperl, in the county of Bosque and State of Texas, have invented certain new and useful Improvements in Plows, of which the following is a specification.

This invention has relation to agricultural implements, and most especially to the type 10 designed for plowing or cultivating the soil, the chief object being to devise a construction which is readily convertible from a turning-plow into a middle-burster or single-stock, according to the nature of the land and the 15 character of work to be performed.

For a full description of the invention and the merits thereof and also to acquire a knowledge of the details of construction of the 20 means for effecting the result reference is to be had to the following description and drawings hereto attached.

While the essential and characteristic features of the invention are susceptible of modification, still the preferred embodiment of the 25 invention is illustrated in the accompanying drawings, in which—

Figure 1 is a perspective view of a plow embodying the invention. Fig. 2 is a horizontal section of the standard at a point immediately above the furrow-bar. Fig. 3 is a detail view of the rear portion of the plow inverted and having the furrow-bar omitted.

Corresponding and like parts are referred to in the following description and indicated 35 in all the views of the drawings by the same reference characters.

The plow-beam 1 may be of usual construction of the type provided with an integral standard 2, which in the present instance is 40 widened at its lower end, as shown at 3, and is received between the complementary bars or members comprising the furrow-bar 4. The bars or plates 4 are arranged upon opposite sides of the widened portion 3 of the standard 2 and are bolted or otherwise secured thereto, and their rear portions project a distance to insure steady running of the plow when in operation. A blade 5 is clamped between the rear extensions of the complementary parts of the furrow-bar 4, and its cutting

edge slopes rearwardly and downwardly, said blade being vertically adjustable to compensate for wear or to admit of its cutting edge being projected to a greater or less distance below the furrow-bar.

55

The stock 6, adapted to receive at its lower end the plow-point of any desired type, is composed of two bars or members transversely spaced and clamped against opposite sides of the standard 2 by means of bolts 7, which when loosened admit of inclining the stock more or less according to the required pitch of the plow and its relation with reference to the furrow-bar. These bolts are arranged to come the one above the other below the curved portion of the beam, so as to prevent vertical movement of the stock, thereby materially bracing the handle-bars and preventing their turning upon the pivot fastening or bolt 9. Handle-bar irons or attachments 8 are arranged upon opposite sides of the standard 2 and are pivotally connected thereto by means of the bolt or fastening 9. The front ends of the irons 8 are brought together and come between the members or elements of the plow-stock 6 and are secured thereto by the bolt or fastening 10, passed through openings in coincident relation to the parts 6 and 8. The rear ends of the irons 8 are upwardly and rearwardly diverged, and the handle-bars 11 are bolted or otherwise secured at their lower ends thereto. Braces 12 connect the handle-bars with the rear portion of the beam 1.

75

By loosening the bolts or fastenings 7 the plow-stock 6 may be turned upon its pivotal connection 10 with the handle-bar irons 8 to secure the desired adjustment of the plow-point or shovel, and a retightening of the fastenings 7 fixes the plow-stock in the required adjusted position.

90

Having thus described the invention, what is claimed as new is—

In a plow or like implement, the combination of the beam having a rearwardly and downwardly curved portion, handle-bar irons 95 arranged upon opposite sides of the curved portion of the beam and having their front ends brought together in front thereof and their rear ends upwardly and rearwardly diverged, handle-bars secured to the rear exten- 100

sions of said irons, a plow-stock composed of corresponding members arranged upon opposite sides of the beam and front ends of the handle-bar irons and pivotally connected to the latter, and bolts connecting the upper ends of the members of the plow-stock and adapted to clamp them against the sides of the said curved portion of the beam, said bolts being arranged the one above the other below the said

curved portion to prevent vertical movement of the said stock and brace the handle-bars, substantially as specified.

In testimony whereof I affix my signature in presence of two witnesses.

JOHNATHAN L. WELDON. [L. s.]
